CLAIM

The ornamental design for a golf shoe cleat, as shown and described.

DESCRIPTION

FIG. 1 is a top perspective view of a golf shoe cleat showing our new design;

FIG. 2 is a bottom perspective view thereof;

FIG. 3 is a bottom plan view thereof;

FIG. 4 is a top plan view thereof;

FIG. 5 is an elevational side view of FIG. 4 thereof;

FIG. 6 is another elevational side view of FIG. 4 thereof; and, FIG. 7 is still another elevational side view of FIG. 4.

The broken line showing of a center line in FIG. 3 is included for the purpose of illustrating only and forms no part of the claimed design.
